UNITED STATES PATENT OFFICE.

LAURITZ W. ANDERSEN, OF WATERBURY, CONNECTICUT, ASSIGNOR TO THE PLUME AND ATWOOD MANUFACTURING COMPANY, OF WATERBURY, CONNECTICUT, A CORPORATION OF CONNECTICUT.

ELECTRIC SHADE-HOLDER.

1,099,783.

Specification of Letters Patent.

Patented June 9, 1914.

Application filed January 14, 1914. Serial No. 812,049.

To all whom it may concern:

Be it known that I, LAURITZ W. ANDERSEN, a citizen of the United States, residing at Waterbury, in the county of New Haven 5 and State of Connecticut, have invented a new and useful Improvement in Electric Shade-Holders, of which the following is a specification.

This invention relates generally to shade 10 holders for electric fixtures and more particularly to a shade holder adapted for attachment to and use in connection with a key socket.

The object of the invention is to provide 15 an exceedingly cheap, and simple shade holder which is adapted for use in connection with the ordinary key socket, and in this connection it will be understood that it can be used with both the turn key and chain 20 pull socket and it will be further understood that it can be used also in connection with a keyless socket and accomplish all of the results required of it and which will be fully explained hereinafter.

Another object of my invention is to provide 25 a shade holder of such construction that the upper portion of the key socket will be exposed instead of covered, thereby exposing the set screw in the socket bushing 30 whereby the said set screw can be adjusted whenever desired.

Another object of the invention is to provide 35 a shade holder attachable to a key socket and when so connected will render the key socket itself less liable to pull apart as it will be understood that all of the so called snap socket shells are liable to part and it is therefore one of the objects of my invention to overcome this weakness.

With these and certain other objects in view 40 my invention consists in the employment of a shade holding shell in the upper end of which fits the key socket, said socket and shade holding shell being connected together and held in their proper positions by 45 means of a screw and clamping ring which bears upon a portion of the key socket and engages the upper end of the shade holder shell.

The invention consists also in certain details 50 of construction hereinafter fully described and pointed out in the claims.

In the drawings forming a part of this specification: Figure 1 is a perspective view

of the shade holder embodying my invention connected to a key socket. Fig. 2 is a detail perspective view of the shade holder with the socket removed. Fig. 3 is a detail view of the clamping ring. Fig. 4 is a detail view of the ordinary key socket and, Fig. 5 is a sectional view of the shade holder arranged upon the key socket, said key socket being shown in elevation.

The socket A is of the usual construction being provided with a key A' at the side, 65 but it will be understood that a chain-pull can be arranged in connection with this socket, or the socket may be of the keyless variety.

The snap sockets as usually constructed 70 comprise a lower portion and an upper portion, the upper portion having a bushing B at its upper end through which passes a set screw C and the lower end of this upper portion is formed with an annular shoulder 75 D and turned-in portion E.

The shade holder comprises a shell F and clamping ring G, the upper end of the shell being threaded as shown at H for the engagement of the threaded portion I of the 80 clamping ring. The lower portion of the shade holder is provided with the usual screws K for fastening the glass-ware or other shade in the holder. This shell F is slotted as indicated at F' to receive the key 85 A' or a suitable opening and be made to receive the pull-chain, and when a keyless socket is used in connection with the holder the slot F' will be entirely omitted. Adjacent the upper end of the shell and at the 90 bottom of the threaded portion H is formed an inwardly projecting shoulder L, upon which rests the lower edge E of the socket and the clamping ring G when screwed down upon the threaded end of the shell engages the shoulder D as most clearly shown in Fig. 5 and in this manner the key-socket, shade-holder shell and clamping ring are bound firmly together at the points where union is desired, and by reference to Fig. 100 5 it will be noted that all of the weight is thrown upon the top portion of the key socket and that the lower portion of said key socket is relieved of all strain and at the same time held firmly in connection with the upper portion.

By means of a shade holder constructed as herein shown and described it will be noted that the upper por-

tion of the key socket is exposed and consequently access can be had to the set screw in the socket bushing. Heretofore nearly all socket covers have completely enveloped the 5 key socket and consequently no opportunity has been afforded for setting the screw in the socket bushing without removing the shade holder and the advantages therefore of my construction will be apparent to every- 10 one skilled in the art to which this invention pertains.

Another feature of my invention is that the screw clamping collar, being removable, can be passed up onto the stem of the bracket 15 while the socket is being wired and brought down afterward and screwed to the body of the shade holder proper, locking it firmly onto the socket and without completely covering said socket as previously explained.

20 The cheapness and simplicity of the invention is of course apparent to everyone consisting as it does of the two parts, the shell and the ring capable of use in connection with the ordinary key socket now in common use.

What I claim is:—

1. A shade holder comprising a shell adapted to receive and envelop the body portion of a key socket, the upper end of said 30 shell being threaded, and a threaded clamp-

ing ring adapted to engage the threaded portion of the shell, said ring being flanged and adapted to engage the top portion of said socket whereby said shell is securely connected to said socket as set forth. 35

2. A shade holder comprising a shell adapted to receive and envelop the body portion of a key socket, the upper end of said shell being provided with a seat adapted to receive a part of the upper portion of the 40 socket body, and a clamping ring adapted to engage the upper end of the socket shell and also a portion of the top of the key socket and hold the same in engagement with the shell. 45

3. A shade holder comprising a shell adapted to receive and envelop the body portion of a socket and having a seat adjacent the upper end of said shell adapted to receive the upper portion of said body, the 50 upper end of said shell being threaded, and a clamping ring engaging the threaded portion of the shell, the upper portion of said ring being adapted to engage the top portion of the socket and hold the same seated within 55 the top portion of the shell, as set forth.

LAURITZ W. ANDERSEN.
